UNITED STATES PATENT OFFICE

WAYLAND CORNELL, OF MINNEAPOLIS, MINNESOTA

FLASH LIGHT

Application filed April 8, 1930. Serial No. 442,670.

This invention relates to flash lights. An object of the invention is to provide a flash light having shock resisting ends so that in case it is dropped the lens and battery and bulb will not be injured.

5 A further object is to provide in a flash light of this character a novel switch.

Referring to the accompanying drawings, which are made a part hereof and on which 10 similar reference characters indicate similar parts,

Figure 1 is a view partly in section of the flash light showing my invention incorporated therein,

15 Figure 2, a view as seen from the left in Fig. 1,

Figure 3, a view as seen from the right in Fig. 1, and

20 Figure 4, a plan view of the switch element.

In the drawings numeral 10 indicates a metallic casing surrounding a fiber tube 11. The casing 10 may be made of any suitable metal such for example as brass plated with 25 nickel to give it an attractive appearance. The inner tube 11 may be of any suitable material but preferably of insulating material.

The inner tube 11 is secured in one end of the casing 10. Secured 30 to one side of the partition is a metal plate 13 having a socket for receiving an electric bulb 15 and having a bent end 14 forming one contact for a switch. A reflector 16 may be secured to the outer side of the plate 12, the

35 reflector and plate 13 being held to the partition 12 as by a rivet 17. The metal casing 10 has threads 18 and 19 formed at its ends. The rear end of the bulb has a back plate 20 which has a threaded portion 21 to fit the 40 threads 18 on the casing 10. A rubber cushion 22 is formed around and at the rear of the back plate 20. This rubber being secured to the plate 20 and forms a cushion for this 45 end of the flash light. A spring 23 may be secured on the inner face of the plate 20 to bear against the rear end of one of the batteries 24. The spring 23, if desired, may be loosely positioned between the rear end of battery and the plate 20 to urge the forward 50 battery into contact with the end of the bulb

15, the spring 23 also forming a ground between one end of the battery and the metal casing 10 of the flash light. A front rubber cap 25 has a reinforcing metal ring 26 embedded therein and has a lens 27 secured in 55 a groove on the inside of the rubber to support this lens resiliently upon the flash light casing, a flange 28 on the rubber ring extending in around the forward edge of the casing of the flash light. The rubber cap is provided with screw threads 29 on its inner side or it may be lined with a metal sleeve having 60 screw threads thereon for holding the cap 25 on the end of the flash light casing. In any case a cushion is provided by the rubber cap 25 which relieves the shock in case the flash light is dropped upon the floor and prevents 65 breaking of the lens 27 or the flash light bulb 25 or injury to either of the batteries 24.

The switch for lighting the bulb comprises 70 a casing 30 secured to the metal sleeve 10 by means of rivets 31. This casing is slotted at 32 to receive the depending end of an operating button 33. This button is preferably of rubber or similar material. The inner end of 75 this button is secured upon a contact element 34 which has one end bent at 35 to make contact with the outer end 14 of the plate 13. The rear end 36 of the switch element is held in either rear or forward position by a hump 80 37 on the casing 10. The casing 10 is cut away at 38 to prevent contact between the outer end 14 of the element 13 and the casing 10 to prevent a short circuit around the switch. It is noted that the batteries 24 are grounded 85 to the plate 20 so that closing a circuit through element 34 and 13 will light the bulb 15. From the foregoing description it is thought the operation and advantages of my 90 flash light should be clear.

This flash light particularly adapts itself for use in theaters in that the rubber button 33 will not injure the gloves worn by an usher in seating patrons in theaters. This 95 rubber button provides sufficient friction on the thumb to make it very easy for the operator to push the switch element 34 forward to light the bulb. The rubber ends 22 and 25 provide shock absorbers in case the flash light should be dropped upon the floor. This not 100

only prevents breaking any element in the flash light but also would make it less noisy.

It will be obvious to those skilled in the art that various changes may be made in my device without departing from the spirit of the invention and therefore I do not limit myself to what is shown in the drawings and described in the specification, but only as indicated by the appended claims.

10 Having thus fully described my said invention, what I claim as new and desire to secure by Letters Patent, is:

1. A flash light comprising a tube of insulating material, a metal casing surrounding the tube, a partition in the tube, a bulb mounted in the partition, a plurality of dry cell batteries in the tube, a metal plate secured to one end of the tube, said metal plate having a spring positioned on one side, 20 said spring being in contact with the rear end of one of the batteries to hold the batteries in circuit making engagement with the bulb, a rubber cushion positioned about said plate, a rubber cap screw threaded upon the front 25 end of the casing, said cap having a lens secured therein, and a reenforcing metallic ring embedded in the said last-named rubber cap, substantially as set forth.

2. A flash light comprising a casing, a bulb secured in said casing, a plurality of dry cell batteries in said casing, a plate mounted on one end of said casing having a spring secured thereto adapted to contact with the rear of one of the batteries to hold the batteries in 35 contact with the bulb, a rubber cushion positioned about said plate and a rubber cap mounted upon the front end having a metallic re-enforcing ring embedded therein, said cap having a lens secured therein, substantially as set forth.

In witness whereof, I have hereunto set my hand at Minneapolis, Minnesota, this 28th day of March, A. D. nineteen hundred and thirty.
